UNITED STATES PATENT OFFICE

ROBERT BACK, OF CHICAGO, ILLINOIS, ASSIGNOR TO THE WAHL COMPANY, OF CHICAGO, ILLINOIS, A CORPORATION OF DELAWARE

DESIGN FOR A BAND FOR A FOUNTAIN PEN OR THE LIKE

Application filed May 4, 1931. Serial No. 39,705. Term of patent 7 years.

To all whom it may concern:

Be it known that I, ROBERT BACK, a citizen of the United States, residing at Chicago, in the county of Cook and State of Illinois, have invented a new, original, and ornamental Design for a Band for a Fountain Pen or the like, of which the following is a specification, reference being had to the accompanying drawings, forming part thereof.

Fig. 1 is a side elevation of a band for a fountain pen or the like showing my new design.

Fig. 2 is a cross-section taken on the line 2—2 of Fig. 1.

I claim:

The ornamental design for a band for a fountain pen or the like, substantially as shown.

ROBERT BACK.
